UNITED STATES PATENT OFFICE.

RUDOLPH M. HUNTER, OF PHILADELPHIA, PENNSYLVANIA.

APPARATUS FOR DYEING.

SPECIFICATION forming part of Letters Patent No. 614,868, dated November 29, 1898.

Application filed June 18, 1896. Serial No. 595,987. (No model.)

To all whom it may concern:

Be it known that I, RUDOLPH M. HUNTER, of the city and county of Philadelphia and State of Pennsylvania, have invented an Improvement in Methods of and Apparatus for Dyeing Textile Fiber, of which the following is a specification.

My invention has reference to the method and apparatus for dyeing textile fiber in the raw state; and it consists of certain improvements fully set forth in the following specification and shown in the accompanying drawings, which form a part thereof.

Heretofore it has been customary in dyeing cotton before being made into yarn to subject the cotton as it comes from the carding-engine to the dye liquor, and after being boiled therein for the necessary length of time it is removed and subjected to a second combing to bring it back into condition capable of being spun. The sliver before being dyed has its fibers brought to a parallel condition by the action of the comb of the carding-engine; but this condition is destroyed by the dyeing operation because the boiling mats and tangles the fiber to such an extent that it must be recombed or carded to again put it into proper condition for spinning. The main objections to this method are that it is slow, expensive by consuming time and labor, is productive of great loss in material due to the second combing, and produces a tendency in the fiber to curl.

The object of my invention set out in this application is to overcome the defects of the method heretofore employed and enumerated above, and in securing these results I employ a bath of dye liquor brought to a temperature just below boiling and then subjecting the sliver as it comes from the carding-engine to the said bath of dye liquor and produce the penetrating action of the dye liquor by causing air or gas to circulate through the dye liquor and fiber being dyed. This may be accomplished by inclosing the sliver in an air-tight dye kettle or vat supplying air to the liquor adjacent to the sliver and creating a partial vacuum above the liquor, so as to cause the equivalent of the boiling action at a low temperature and without the attendant defects. In place of employing a partial vacuum to induce circulation of the air I may force the

air or gas through the liquor and cause it to pass through the sliver to be dyed, as this would secure the full penetration of the liquor into the sliver. A given amount of warmth in the dyeing operation is advantageous and practically necessary; but an excess or that equal to 212° Fahrenheit is injurious, since it produces matting of the cotton. The lack of the boiling action at atmospheric temperature is compensated for by the forced circulation due to the air, whether the same be sucked or forced through the liquor. In forcing the air through the liquor the subdivision would hardly be as great as in causing its circulation by creating and maintaining a partial vacuum within the vat above the liquor, and I would say, furthermore, that by the employment of this partial vacuum I may cause the boiling effects at a temperature less than 212° Fahrenheit, and consequently in this manner avoid matting to a greater or less extent and without causing positive circulation of air through the dye liquor and cotton.

In the processes heretofore in practice the matted cotton had to be recombed to straighten its matted and curled fibers, and this not only caused expense in time and labor, as I have before pointed out, but necessitated a serious loss of good fiber and which by the process of dyeing in the skein would be saved. The losses in dyeing in the sliver or raw condition were equal to if not greater than the increased expense of dyeing in the skein, and hence there was no object or advantage in dyeing in the raw state. By the process herein set out, however, this is changed, as the desired object may be secured without loss of material and with a minimum of labor and expense.

In carrying out my invention with suction I provide a vat to contain the dye liquor provided with steam-pipes to heat the liquor and an air-tight cover to seal the top. I also provide a frame adapted to be lowered into the vat and provided with a series of mandrels, upon which the slivers are wound or coiled. I prefer to cause these mandrels to rotate slowly during the dyeing operation to bring to the upper side all portions alike. While so rotating in the dye liquor I cause a partial vacuum to be created in the upper part of the vat, and thereby cause the liquor to burst into

agitation at a temperature below that of 212° Fahrenheit. This agitation may also be increased by supplying air to the interior of the mandrels and allowing it to escape through 5 apertures into the dye liquor and pass upward through the material being dyed.

In carrying out my invention with compressed air I force the air under pressure through the pipes moving with the mandrel-10 carrying frame into and through the perforated sides of the mandrels and thence into the dye liquor. The air becomes heated in contact with the dye liquor, and in passing through the sliver upon the mandrel insures 15 the proper penetration of the same at a temperature below 212° Fahrenheit. The mandrels in rotating bring all parts of the sliver to position to be acted on equally, and this is most important, since air will not descend 20 and escapes into the dye liquor only within the space bounded by the wound sliver and at the mandrel. The mandrels are removable from the frame of the vat and adapted to be inserted in a winding-machine when the sliver 25 is being wound upon them, and are further provided with a movable or adjustable support, so that after the winding operation and before the dyeing operation begins the sliver may be loosened, so as to hang loosely upon 30 the rotating mandrel. While I prefer to rotate the mandrels in the dyeing operation, I do not confine myself thereto.

My improvements will be better understood by reference to the accompanying drawings, 35 in which—

Figure 1 is an elevation of my improved apparatus. Fig. 2 is a cross-section of same on line $x-x$ of Fig. 3. Fig. 3 is a sectional elevation on line $y-y$ of Fig. 2, and Fig. 4 is a 40 sectional elevation of the mandrel for holding the sliver before and during the dyeing operation.

A is the dye-vat, and has steam-coils B at the bottom.

45 C is a lid or cover, which may be adjusted with a fairly packed or tight joint c.

D is the frame for carrying the mandrels, and is preferably formed of copper or bronze and made of tubes. It is made box-shaped 50 and has a lower side pipe F, provided at intervals, nipples H, and flanges G. These nipples communicate through the pipes of the frame with the air-supply pipe D', which projects off laterally from the top of the frame, 55 so as to extend outside the vat in the dyeing operation. This extension is provided with a valve D² and a flexible downward extension D³, adapted by a coupling D⁴ to be connected with the pressure-pipe O, leading directly or 60 through a reservoir P' to the pump P. The suction-pipe S of the pump may connect with a vacuum-chamber Q and this by a pipe R with the upper part of the vat. A valve r and pipe R' may be employed to control the 65 escape of the air into the atmosphere when the pressure is alone required in operating my process. The chamber Q may be provided

with a vacuum-valve g to control the extent of vacuum and insure its remaining constant. A valved suction-pipe S' may be employed 70 when pressure alone is used.

Returning to the frame D, I employ a support J² on the opposite side to the tube F, and this is provided with a series of tubular bearings J³, directly opposite to the nipples H, 75 and in these I journal spindles K, having sprocket-wheels l on the outer ends. On the other ends of the spindles K, I arrange springs L, acting upon a collar L' to press it toward a pin k. About the sprocket-wheels l I pass 80 a chain d and employ intermediate guide or idler wheels e to insure the chain against slipping off of wheels l. When the frame D is adjusted within the vat, the chain d rests upon the sprocket-wheel M, which is secured 85 to the inner end of a shaft m, passing through a stuffing-box M' in the side of the vat and provided on the outside with a hand-wheel or crank M². By turning the shaft m by hand or power the spindles K may be rotated. 90

The mandrel I is clearly shown in Fig. 4 and consists of an inner perforated tube I² and an outer perforated tube I¹, connected together at one end by an annular head I³ and at the other end by a screw-plug I⁴. Surrounding the mandrel, between the middle and one end, I arrange an annular wooden disk J'. Loosely supported near the other end I arrange a similar wooden disk J, but make it adjustable longitudinally, and provide it with 100 two heavy-wire spring-catches j, adapted to catch in apertures i i' in the mandrel's outer tube I¹ for adjustment. After the sliver has been wound upon this mandrel in connection with the carding-machine I adjust the movable disk J toward the disk J' for the purpose of loosening up the sliver and bringing it to a condition to dye uniformly. When this is done, a cage composed of two parts N N is slipped over the ends of the mandrel and the 110 parts fastened together to prevent the sliver falling away. This cage may be simply of wire or covered with an open-woven fabric n, which would have a greater tendency to break up the air passing through the dye liquor, 115 and thus make the dyeing operation more uniform. If desired, the cage may be composed wholly of fabric, like a bag, with a hole in its end and tied around the mandrel at its open end. The mandrel so loaded and adjusted is applied to the frame D by entering the end of the spindle K into the recessed end of plug I⁴, which has notches to receive the pin k, and thus insure the mandrel rotating 120 with the spindle and then pressing back the spindle and compressing the spring L until the other end I³ can be placed over the nipple H, as shown in Fig. 2. It will be understood that a number of such loaded mandrels are inserted upon the frame before it is lowered into the vat. 125

When the frame is lowered into the dye-vat by any suitable hoisting apparatus, such as a light crane, the lid C of the vat is placed

on a connection D⁴, completed with pipe O. The valve d² is then opened and the admission of air under pressure is controlled by the valve D². It is evident that it may be controlled by valve d² instead, if desired. The compressed air is thus delivered through the piping of the frame D and through nozzles H into the hollow mandrels I, from which it escapes through the holes to the inner side of the cotton wound thereover, causing the dye liquor to penetrate the same and perform substantially the effect of the strong boiling action without its objectionable qualities. While this operation is going on the dye liquor is preferably kept at a temperature somewhat below boiling and the hand-wheel M² is rotated, so as to slowly turn the mandrels, and thereby insure all portions of the cotton being subjected to the action of the dye liquor to the same degree. By this process I secure the desirable results of the heat from the dye liquor without the objectionable results from excessive temperature which is always present when the dye liquor is brought to 212° Fahrenheit. If pressure alone is employed, the lid C may be left off, but when the circulation of the air is induced partly or wholly by the creation of a partial vacuum the lid C must be placed on the vat and by the packing c make the vat practically airtight or sufficiently so to secure the circulation. When this is done, the partial vacuum produced in the vacuum-chamber Q is caused to exert its influence upon the interior of the vat and induce a circulation of air through the spindles I. When pressure alone is employed, the valved pipe S' is left open. If the lid C is on, then the valve r is opened. If the circulation is to be secured by the partial vacuum alone, then the pipe D³ is left open to the atmosphere. The advantage of employing the inner perforated tube I² as well as the outer perforated tube I' is to secure a uniform distribution of the air, whether it be circulated by pressure or vacuum, and this insures the uniform dyeing operation. After the dyeing operation the lid C is removed, the coupling D⁴ separated, and the frame D lifted out. The mandrels are then disconnected, the cage N N is removed, and the dyed cotton taken off. The result of this operation is a most perfect and uniform dyeing without matting or curling of the cotton, and hence without loss. The fiber of the cotton lies straight and in a most satisfactory condition for spinning.

I do not confine myself to the details of the apparatus herein set forth, though I prefer it as being excellently adapted for the purpose. Having now described my invention, what I claim as new, and desire to secure by Letters Patent, is—

1. In apparatus for dyeing raw fibrous material, the combination of a vat having provision at the top for the escape of air and vapor and containing dye liquor, a removable frame adapted to be inserted and removed

from the top of said vat, one or more detachable hollow perforated spindles carried by the said frame independently of the vat and upon which the raw fibrous material is loosely wound and by which it is held continuously submerged in the dye liquor, and means to cause air or gas from outside the vat to flow continuously through the spindles and from the interior thereof outwardly into the dye liquor within the material supported upon said spindles to produce in effect a boiling action at a low temperature and a positive circulation of the dye liquor at the same time both inwardly and outwardly between the strands of the fibrous material whereby it penetrates the raw fibrous material without passing through the spindles or leaving the vat.

2. In apparatus for dyeing raw fibrous material, the combination of a vat having provision at the top for the escape of air and vapor and containing dye liquor, a removable frame adapted to be inserted and removed from the top of said vat, one or more detachable hollow perforated spindles carried by the said frame independently of the vat and upon which the raw fibrous material is loosely wound and by which it is held continuously submerged in the dye liquor, means for rotating the spindles upon the frame and about their own axes, and means to cause air or gas from outside the vat to flow continuously through the spindles and from the interior thereof outwardly into the dye liquor within the material supported upon said spindles to produce in effect a boiling action at a low temperature and a positive circulation of the dye liquor at the same time both inwardly and outwardly between the strands of the fibrous material whereby it penetrates the raw fibrous material without passing through the spindles or leaving the vat.

3. In apparatus for dyeing raw fibrous material, the combination of a vat, a removable frame adapted to be inserted and removed from said vat, one or more detachable hollow perforated spindles rotatably journaled upon the said frame and upon which the raw fibrous material is loosely supported and rotated, means for rotating the said spindles upon the frame and about their own axes, and means to cause air or gas to flow through the spindles into the dye liquor while rotating whereby a large volume of air or gas is made to flow through the dye liquor to cause it to penetrate the raw fibrous material without entering the spindle or leaving the vat.

4. In apparatus for dyeing raw fibrous material, the combination of a vat, a removable frame adapted to be inserted and removed from said vat, one or more detachable hollow perforated spindles carried by the said frame upon which the raw fibrous material is loosely supported, a removable pervious cage surrounding the middle portion of each spindle for confining the raw fibrous material in a loose condition upon the spindles and per-

mitting its strands to shift relatively to each other, and means to cause air or gas to flow through the spindles into the dye liquor whereby the said dye liquor is made to penetrate the raw fibrous material and into and out of the cages without entering the spindles or leaving the vat.

5. In apparatus for dyeing raw fibrous material, the combination of a vat, a removable frame adapted to be inserted and removed from said vat, one or more detachable hollow perforated spindles carried by the said frame upon which the raw fibrous material is loosely supported, removable means surrounding the middle portion of each spindle for confining the raw fibrous material in a loose condition upon the spindle consisting of a pervious covering or cage made in detachable parts approaching the spindle upon each side of its center, and means to cause air or gas to flow through the spindles into the dye liquor whereby the dye liquor is made to penetrate the raw fibrous material without flowing through the spindle or leaving the vat.

25. 6. In apparatus for dyeing raw fibrous material, the combination of a vat, a removable frame adapted to be inserted and removed from said vat, one or more detachable hollow perforated spindles carried by and removable with the said frame upon which the raw fibrous material is loosely supported and provided with annular disks relatively adjustable to or from each other over which the raw fibrous material is wrapped and sustained away from the perforations of the spindle, and means to force air or gas to flow through the spindles into the dye liquor to cause the dye liquor to penetrate the raw fibrous material without leaving the vat.

40. 7. In apparatus for dyeing raw fibrous material, the combination with a dye-vat, one or more hollow perforated spindles supported within the vat and normally submerged in the dye liquor and upon which the raw fibrous material to be dyed is very loosely wound, means for rotating the said spindles while submerged upon their own axes, and means for causing air or gas unmixed with dye liquor to flow through the spindles from the inside 45 outwardly whereby the dye liquor is fully circulated through the material without leaving the vat.

8. In apparatus for dyeing raw fibrous material, the combination with a dye-vat, means for heating the dye liquor in the vat to a temperature below 212° Fahrenheit, one or more hollow perforated spindles normally supported within and submerged in the dye liquor in the vat and upon which the raw fibrous material to be dyed is very loosely wound, means for rotating the said spindles upon their longitudinal axes while wholly submerged, and means for causing air or gas to flow through the spindles into the dye liquor, 60 whereby said dye liquor is fully circulated through the material without leaving the vat.

65. 9. In apparatus for dyeing raw fibrous ma-

terial, the combination with a dye-vat, one or more hollow perforated spindles supported and submerged in the dye liquor within the 70 vat and upon which the raw fibrous material to be dyed is loosely wound, means for rotating the said spindles upon their longitudinal axes, removable means rotating with said spindles for confining the raw fibrous material in a loose condition upon the spindles and permitting its strands to shift relatively to each other, and means for causing air or gas to flow through the spindles into the dye liquor while submerged in the dye liquor 80 whereby the dye liquor is circulated through the material without leaving the vat.

10. 10. In apparatus for dyeing raw fibrous material, the combination of a vat, means to heat the dye liquor, a normally stationary frame 85 removably adapted to the interior of the vat and having a tubular part formed with one or more horizontal tubular nozzles and an air or gas supply pipe, one or more horizontal hollow perforated spindles for holding the 90 fibrous material detachably adapted to said nozzles, means carried by the frame acting upon the opposite ends of said spindles for temporarily holding them horizontally in place upon the frame, and means to circulate 95 air or gaseous media through the tubular nozzles supply - pipe and spindles into the dye liquor in the vat whereby the dye liquor is circulated through the loose material without leaving the vat.

11. 11. In apparatus for dyeing raw fibrous material, the combination of a vat, means to heat the dye liquor, a normally stationary frame 105 movably adapted to the interior of the vat and having a tubular part formed with one or more horizontal tubular nozzles and an air or gas supply pipe, one or more horizontal hollow perforated spindles for holding the 110 fibrous material detachably adapted to said nozzles, means extending to the outside of the 115 vat for rotating the spindles upon their longitudinal axes, means carried by the frame acting upon the opposite ends of said spindles for temporarily holding them horizontally in place upon the frame, and means to circulate 120 air or gaseous media through the tubular nozzles supply-pipe and spindles into the dye liquor in the vat whereby the dye liquor is circulated through the loose material without leaving the vat.

12. 12. A spindle for a dyeing apparatus consisting of a hollow perforated tube, combined with two annular disks or supports encircling the spindle at a distance from each end and over which the material to be dyed is wound, 125 the said disks or supports being relatively adjustable to or from each other whereby the tension of the material dyed may be adjustable by the said disks or supports, and a detachable inclosing pervious envelop surrounding the tube and inclosing the disks and loosely-wound materials being dyed.

13. 13. A spindle for a dyeing apparatus consisting of a hollow outer perforated tube

closed at both ends, and an inner perforated tube open at one end whereby the pressure of the air or gas is evenly distributed at the surface of the outer tube, combined with two 5 annular disks or supports encircling the outer tube at a considerable distance from each end for loosely sustaining the material to be dyed at a distance from the outer tube and relatively adjustable to or from each other upon 10 the outer tube and within the material being dyed.

14. In a spindle structure for a dyeing-machine, the combination of outer tube I' having perforations, the inner tube I² also having 15 perforations, head I³ attached to one end of the inner tube and supporting the outer tube, head I⁴ secured to the opposite ends of both inner and outer tubes, and annular supports over which the material to be dyed is loosely 20 wound longitudinally of the spindle made relatively adjustable and supported upon the outer tube at a distance from each end.

15. In a spindle structure for a dyeing-machine, the combination of outer tube I' having 25 perforations, the inner tube I² also having perforations, head I³ attached to one end of the inner tube head I⁴ secured to the opposite ends of both inner and outer tubes, and annular supports J, J' upon the outer tube at a 30 distance from each end and over which the material to be dyed is loosely wound longitudinally made relatively adjustable upon the outer tube by means of spring-catches j upon one of the disks.

35 16. In apparatus for dyeing fibrous material, the combination of a dye-vat, a hollow horizontal perforated spindle upon which the material to be dyed is loosely wound and during the dyeing operation continuously sus- 40 tained below the liquid-level having communica- tion outside of the vat to permit supply

of air or gas to the spindle, means to keep the temperature of the dye liquor to a temperature below boiling, and continuously-acting suction-creating devices connecting with 45 the vat above the level of the dye liquor for simultaneously and continuously causing the air or gas from outside the vat to flow into and through the spindle and continuously into and through the dye liquor to circulate 50 the said dye liquor through the material and prevent it flowing through the spindle or leaving the vat.

17. In apparatus for dyeing raw fibrous material, the combination of a dye-vat contain- 55 ing dye liquor, a substantially tight lid for the vat, a hollow perforated spindle upon which the material to be dyed is loosely wound continuously submerged in the dye liquor and connected by a tubular extension outside 60 the vat to permit a continuous supply of air or gas to the interior of the spindle, means to keep the temperature of the dye liquor to a temperature below boiling, and continuously-acting suction-creating devices connecting 65 with the vat above the level of the dye liquor for creating a partial vacuum continuously above the dye liquor within the vat during the dyeing operation and a continuous pressure within the hollow spindle for causing the 70 air or gas to flow from outside the vat through the spindle continuously into and through the dye liquor and circulate the dye liquor continuously through the material being dyed without flowing through the spindle or leaving 75 the vat.

In testimony of which invention I hereunto set my hand.
